[57] CLAIM

The ornamental design for a cover for a plate or the like, substantially as shown and described.

DESCRIPTION

FIG. 1 is a top perspective view of a cover for a plate or the like showing my new design.

FIG. 2 is a top plan view of the design.

FIG. 3 is a side elevational view of the design.

FIG. 4 is a bottom plan view of the design.

FIG. 5 is a cross-sectional view taken along the line 5—5 of FIG. 2.

The external surface of the design constitutes a surface of revolution and thus the side elevational view of FIG. 3 is typical regardless of which portion of the design is viewed in this plane.

FIG. 1.FIG. 2.FIG. 3.FIG. 4.FIG. 5.
